SPOON OR SIMILAR ARTICLE

William H. Gerth, New York, N. Y., assignor to Oneida
Ltd., Oneida, N. Y., a corporation of New York

Application November 7, 1955, Serial No. 38,783

Term of patent 14 years

(Cl. D54—12)

FIG. 1.

FIG. 3.

FIG. 2.

FIG. 4.

FIG. 5.

FIG. 6.

Fig. 1 is a front elevational view of a spoon showing my new design;

Fig. 2 is a rear elevational view;

Fig. 3 is a side elevational view; and

Figs. 4, 5 and 6 are sections taken on the respective lines 4—4; 5—5 and 6—6 of Fig. 1.

The essential features of my design for a spoon or similar article reside in the configuration of the handle in combination with the particular type of ornamentation as applied thereto.

I claim:

The ornamental design for a spoon or similar article, substantially as shown and described.
